D. H. WINSLOW.

ROAD SCRAPER.

APPLICATION FILED JAN. 14, 1919.

1,297,430.

Patented Mar. 18, 1919.

UNITED STATES PATENT OFFICE.

DAVID HERBERT WINSLOW, OF RALEIGH, NORTH CAROLINA.

ROAD-SCRAPER.

1,297,430.

Specification of Letters Patent. Patented Mar. 18, 1919.

Application filed January 14, 1919. Serial No. 271,137.

To all whom it may concern:

Be it known that I, DAVID HERBERT WINSLOW, a citizen of the United States, residing at Raleigh, in the county of Wake and State of North Carolina, have invented a new and useful Road-Scraper, of which the following is a specification.

This invention relates to a machine for use in repairing roads, one of the objects 10 of the invention being to provide a simple, inexpensive and efficient structure which, when drawn over a road, will remove ridges and other raised portions by first loosening the surface material and then scraping it 15 into depressions after which, as a part of the one operation, the material thus distributed is packed so as to leave the road smooth and free from all undesirable depressions and raised portions.

20 A still further object is to provide a machine of this character which will operate efficiently on all kinds of rural roads whether they be of ordinary soil, of sand-clay, gravel or macadam.

25 Another object is to provide a road machine of this character which can be repaired easily, and which can be readily manipulated, the said machine operating in the same manner as a plane to loosen and shave 30 off elevated portions and fill in the depressions.

With the foregoing and other objects in view, which will appear as the description proceeds, the invention consists of certain 35 novel details of construction and combinations of parts which will be hereinafter more fully described and pointed out in the claim it being understood that various changes may be made in the construction 40 and arrangement of the parts without departing from the spirit, or sacrificing any of the advantages of the invention as set forth in the appending claim.

In the accompanying drawings the preferred form of the invention has been shown.

In said drawings:

Figure 1 is a plan view of the device.

Fig. 2 is a section on line 2—2 Fig. 1.

Referring to the figures by characters of 50 reference 1 designates a front cross beam,

2 an intermediate cross beam and 3 a rear cross beam, all of these beams being connected at their ends by longitudinal side beams 4 to the front ends of which are connected the ends of a chain 5 to which the 55 draft animal or a tractor may be connected.

Spikes 6 which are preferably case hardened are driven through the beams 1 and 2 and are arranged in longitudinal series. The points of these spikes extend below the 60 beams 1 and 2 so as to dig into the surface of the road and loosen the material thereof. A scraping blade 7 is secured to and covers the front face of the rear beam 3. Arranged back of the beam 3 is a packing section 65 formed of side strips 8 to the bottom faces of which are secured the ends of packing strips 9 which are inclined upwardly and forwardly and arranged in lapped relation as shown in Fig. 2. Chains 10 or the 70 like connect the rear ends of beams 4 to the front ends of the strips 8.

In using the device herein described it is placed on the surface of the road and drawn forward by any means desired. The 75 points of the spikes 6 will dig into the surface of the road so as to loosen the material. The blade 7 following these spikes will act as a slicer and scraper, engaging the loosened material and scraping away the ridges or 80 raised portions. The material thus scraped will be drawn along and deposited in the depressions in the surface of the road. The packing section following the blade 7 will ride over the material thus distributed and 85 will pack it tightly, leaving a smooth road surface free of all undesirable depressions and raised portions. If desired any suitable weight may be placed on the packing section. 90

What is claimed is:

A road scraper including beams, spikes carried by the beams and projecting therebelow for loosening the surface material of a road, another beam back of the spike carrying beams, a scraping blade upon the front face thereof, connections between the beams, all of said beams being extended transversely of their path of movement and co-operating to limit the downward movement 100

of the spikes into the surface material of the road, connected packing strips back of the beams and arranged in lapped relation, said strips being inclined upwardly and forwardly and movable laterally and vertically relative to the beams, and flexible connections between said strips and the beams.

Copies of this patent may be obtained for five cents each, by addressing the "Commissioner of Patents, Washington, D. C."

In testimony that I claim the foregoing as my own, I have hereto affixed my signature in the presence of two witnesses.

DAVID HERBERT WINSLOW.
